UNITED STATES PATENT OFFICE.

EDGAR L. STERN, OF SAN FRANCISCO, CALIFORNIA.

FOLDING BOX.

Application filed April 27, 1921. Serial No. 484,921.

To all whom it may concern:

Be it known that I, EDGAR L. STERN, a citizen of the United States, residing at city and county of San Francisco and State of California, have invented a new and useful Improvement in Folding Boxes, of which the following is a specification.

This invention relates to a box and particularly pertains to improvements in folding paper boxes.

Heretofore many paper boxes have been formed having side and end walls fitted with locking tongues and receiving slits by which the walls may be secured in perpendicular relation to the bottom of the box. In many instances the walls have been so designed as to be folded at their locked positions so that they may be readily erected to form the desired container. It has been a common defect in this class of boxes, however, that the locking tongues or other portions of the box must be bent in order to cause the sides to lie in their folded position, thus making it necessary that the assembled box will be distorted and it is the principal object of the present invention to provide a box blank, the ends and sides of which may be factory assembled and thereafter folded in a manner to prevent bending or distortion of the box sides, at the same time insuring that the box sides and ends may be instantly erected to form the container without trace of having been folded and in a manner to prevent separation of the end and side members.

The present invention contemplates the use of a blank preferably formed with cardboard which has a rectangular body portion, the sides of which are bounded by side and end members adapted to be erected to form a wall around the perimeter of the body panel, the end members being fitted with locking tongues which may be projected through slots in the side members in a manner to permit the side and end members to be folded flat against the body member while the tongues are in their locking position and without allowing the various members to become accidentally unlocked.

The invention is illustrated by way of example in the accompanying drawings, in which:

Figure 1 is a view in perspective illustrating the completely assembled box member.

Fig. 2 is a view in plan illustrating the blank formation from which the box is formed.

Fig. 3 is a plan disclosing the assembled and folded blank.

Fig. 4 is an enlarged fragmentary view in plan showing one corner of the folded box with parts broken away to more clearly disclose the position of the locking tongue when the box is folded.

Fig. 5 is an enlarged view in section as seen on the line 5-5 of Fig. 4 showing the manner in which the locking tongue extends through the folded box without being unduly bent or distorted.

Referring more particularly to the drawings, 10 indicates a box blank having a central rectangular panel 11. This panel is bounded on its four sides by side score marks 12 and 13 and end score marks 14 and 15. Formed as continuations of the central panel and along the score marks 12 and 13 are side panels 16 and 17 which form the side walls of a box portion 18. It is to be understood that two of these box members are used in forming a complete box, one providing the top and the other the bottom, while the side and end walls of the bottom box member telescope within the top box member. Formed as continuations of the opposite ends of the panel 11 are end panels 19 and 20. The panels 16, 17, 19 and 20 are all of the same height and are of lengths plural and corresponding to the length and width of the panel 11. Locking tongues 21 are formed as continuations of the end members 19 and 20. These tongues are separated from the end panels by score marks 12' and 13' and it will thus be evident that when the side and end panels are folded up along the lines 12 to 15 inclusive, these panels will form a rectangular inclosure with the panel 11 for a bottom.

In order to secure these panels in this position the tongues are adapted to pass through slots 22 formed near the ends of the side panels 16 and 17. It will be observed that a neck portion 24 is adapted to be locked in the slots 22 of the side panels so as to hold the heads against removal. The tongues agree in width with the end panels and in length with the width of the side panels and are formed with diagonal locking lips 25. Attention is directed to the fact that in the present case the panels of the box and the tongues are only folded on the score marks 12 to 15 inclusive, and 12' and 13', thus insuring that when the box is completed none of the sides nor the tongues will be unnecessarily bent or dis-

105

110

torted and that the tongues will act to hold the panels in rigid relation to each other and thus the side and end panels to substantially conform to the perimeter dimensions of the body panel 11.

The slots 22 cut in the side panels are especially formed so as to accommodate the tongues when the box is folded or unfolded and to insure that after the tongues are in place they will not be accidentally withdrawn. The slots are formed with a main arcuate portion *a*, a short slotted end portion *b*, adjacent the marginal edges of the panels and an arcuate end portion *c* at the opposite end of the slot *a* and adjacent the inner corners of the panels. The portion *a* is described by an arc emanating from the outer corner of the end panel and is of a length substantially agreeing with the width of the heads 23 of the tongue.

Due to the peculiar curvature of the slots 22 and the slotted ends *b* and *c* thereof, the sides and ends of the box may be connected by the tongues to assume the position shown in Fig. 3. In other words, in assembling the box the sides 16 and 17 are folded over the body panel. The ends 19 and 20 are then partly bent over the body panel and sides and the tongues are inserted through the slots. The ends 19 and 20 are then completely folded against the body panel over the sides. During this period it is seen that the lip *x* of the slot would be uppermost and the lip *y* the lowermost with the tongue positioned therebetween. However, due to the slotted ends of the slots and curvature thereof, these lips reverse their position during the erecting operation. In other words, the lip *y* during the first period of erecting will be the innermost lip and the lip *x* the outermost one. Immediately before the box is completely erected the lips gradually change position until the lip *y* will be the outermost lip and the lip *x* the innermost one, which position they will maintain when the box is completely erected.

It should be stated that in erecting the box, the face of the portions 25 of the tongues come in contact with the outer surface of the sides. This is somewhat of a cam action and serves to maintain the sides and ends in position once they are erected.

In operation of the present invention, the box blank is cut as shown in Fig. 2, thereafter it may be assembled by first folding the side panels along the score lines 12 and 13 until these panels are entirely folded down over the body panel 11. The end panels are then folded over the body panel 11 and the previously folded side panels. The end panels are creased along the score marks 12' and 13' until the tongues will lie flat against the inner faces of the end panels. The side panels may then be raised and the tongues of the end panels inserted through

the slots 22. During this operation the upper portions of the heads 23 will pass through the end portions *b* of the head, and at the same time the cut *c* will allow the slot to sufficiently spread to permit the head 70 of the tongue to pass completely through the slot without being bent or otherwise distorted. Attention is directed to the fact that this movement to insert the tongue through the slot is in a direction toward the longitudinal center of the box blank and in plane substantially parallel to that of the face of the box blank so that when the box is assembled and folded the tongues will lie in the folded positions indicated by dotted lines 75 in Fig. 3. When it is desired to use the box the side panels 16 and 17 may be engaged and drawn upwardly and outwardly. As this takes place the corners of the side panels will act to force up the end panels and this will result in swinging the tongues from a plane parallel to the folded end panel to a plane at right angles to the side panels. These tongues will, at the same time act to hold the side and end panels at right angles 80 to each other and to the body panel 11. By using two of the box members 18 suitably varying in diameter, a complete box may be formed having a top and bottom and sides. 85

It will thus be seen that the box structure here disclosed, while requiring no more paper stock than is usually required in boxes of this class, at the same time provides a folded box which may be conveniently 100 handled and readily manipulated to produce a desired container.

While I have shown the preferred form of my invention as now known to me, it will be understood that various changes in the 105 construction, combination and arrangement of parts may be made by those skilled in the art without departing from the spirit of the invention as claimed.

Having thus described my invention, 110 what I claim and desire to secure by Letters Patent, is:

1. A box comprising a rectangular body panel, end panels formed at the opposite ends of said panel, side panels, tongues formed on the ends of the end panels, slots formed in the side panels for receiving the tongues, said slots permitting the side and end panels to be folded over the body panel and interlocked and instantly erected when interlocked without bending the tongues and co-operating means on the tongues and slots whereby the panels will be held rigid when interlocked and in their erect position and to resist collapsing thereof back to their positions. 115

2. A box comprising a rectangular body panel, side panels extending along the opposite sides of the body panel and defined by score marks, end panels extending along 120

the opposite ends of the body panel and defined by score marks, tongue members extending from the opposite ends of the end panels and defined from the end panels by 5 a continuation of the side panel score marks, slots within the ends of the side panels and with which the said tongues are adapted to interlock, said slots being so formed as to permit the said tongues to be inserted there- 10 in when the side and end panels are folded over the body panel, said slots also permitting the side and end panels to be extended perpendicularly to the body panel without disengaging the tongues from the slots or 15 bending said tongues, and co-operating means formed on the tongues and slots whereby to maintain the side and end panels rigid when interlocked and in erected position and to resist collapsing of said side 20 and end panels back onto the body panel while erected and interlocked.

3. A box comprising a rectangular body panel, side and end panels disposed around the perimeter of the body panel, locking 25 tongues formed as continuations of the end panels, receiving slots formed in the side panels, the said tongues and slots being so formed as to permit the end and side panels to be folded against the body panel and 30 interlocked and to be instantly erected to form a box without disengagement of the tongues and slots and co-operating means formed on the tongues and slots whereby

to maintain the side and end panels rigid when interlocked and in erected position 35 and resist collapsing thereof back onto the body panel while erected and interlocked.

4. A box comprising a rectangular body panel, end panels formed at opposite ends of said body panel, side panels formed at 40 opposite sides of said body panel, tongues formed at the opposite ends of the end panels, slots formed within the ends of the side panels for receiving the tongues, said slots being so formed as to permit the side 45 and end panels to be folded over the body panel and interlocked by the insertion of said tongues into the slots, a locking lip formed on each of said tongues, said lips being engageable with the outer surface of 50 said side panels, and adapted to permit the side and end panels to be extended perpendicularly to the body panel without disengaging the tongues from the slots, said 55 lips, when the side and end panels are in extended position, being adapted to maintain the side and end panels rigid whereby to resist collapsing of said panels back onto the body panel.

In testimony whereof I have hereunto 60 set my hand in the presence of two subscribing witnesses.

EDGAR L. STERN.
